UNITED STATES PATENT OFFICE.

ABBOT AUGUSTUS LOW, OF NEW YORK, N. Y.

CLOSING-CAP FOR VESSELS.

SPECIFICATION forming part of Letters Patent No. 665,334, dated January 1, 1901.

Application filed April 16, 1900. Serial No. 13,000. (No model.)

To all whom it may concern:

Be it known that I, ABBOT AUGUSTUS LOW, a citizen of the United States, and a resident of New York, (Brooklyn,) in the county of 5 Kings and State of New York, have invented a certain new and useful Closing-Cap for Vessels, of which the following is a specification.

My invention relates to closing-caps for vessels which are provided with a barrel, internally-disposed flange and dome rising above the top of said barrel from the inner edge of the flange and above the dome, a discharge tube or spout provided with a cap to close it, and to an internal shell conforming generally 15 to the shape of the exterior cap and provided with means for securing the whole upon a vessel and for removing the same when the vessel is to be discharged; and it consists in certain elements and combinations fully set forth in 20 the specification and claimed at the end thereof.

In order that persons skilled in the art to which my invention appertains may understand, construct, and use my invention, I will 25 proceed to describe it, referring to the drawings, in which—

Figure 1 is a vertical central section. Fig. 2 is a top view with the cap removed to show perforations in the top of the internal shell. 30 A is the vessel-mouth, B the walls of same, and C the barrel of the exterior cap, furnished with a screw-thread to match the thread upon the vessel-neck.

H is an internally-disposed flange above the 35 barrel C.

I is a dome or chamber rising from the inner edge of the flange H.

J is a tube rising from the crown of the dome I for discharging the vessel.

40 K is a closing-cap for the tube J.

D is a packing in closing-cap K.

M is a shell located within the exterior cap and of similar shape in part.

O is a flange located at the base of shell M 45 and turned outward to pass under the internally-disposed flange H on the exterior cap. This flange O is provided with downwardly directed rims P and embraces a packing piece Q.

The top of shell M is wholly or partially 50 closed, according to the character of the materials contained in the vessel. I have shown in the figures perforations R in the top W similar to those used in pepper and salt distributors. The inside lining or shell serves 55 to shield the exterior cap from the injurious effects or action of the contents of the vessel and also to control the packing both at the top and bottom joints, as it wholly controls the function of sealing the vessel. 60

The sealing is secured by screwing the upper cap K on tube J and by screwing the barrel C down upon the walls of the neck B, thus forcing the packing in flange O at the base of internal shell M upon said walls by means of 65 the flange H and also by means of the pressure exerted upon the top of shell M by means of cap K as the cap K bears upon the top of said shell, thus forcing it downward and at the same time making a tight joint at that 70 place.

Having now fully described my invention and the manner in which I have embodied it, what I claim as new and as of my invention, and desire to secure by Letters Patent, is— 75

1. In a closing-cap for vessels, the combination consisting of the barrel as C, flange as H, dome or chamber as I, discharge-tube as J, closing-cap as K, and means for securing to and removing same from the vessel, internal shell as M, provided at its base with flange as O, and rim as P, adapted to inclose packing as Q between flange O and the top of the walls of the vessel, and at its top provided with perforations R on its upper surface at 85 W, and constructed to engage with packing in cap K, all constructed, arranged and combined when applied to the mouth of a vessel, to seal the same hermetically and when closing-cap is removed to discharge the contents 90 through the perforations R, substantially as specified.

2. In a closing-cap for vessels, the combination consisting of the exterior cap, means for securing to and removing same from the 95 vessel, and provided with centrally-disposed flange, chamber and discharge-spout above the barrel of same, and means for opening and

closing it in use, an internal shell carrying
packing at its base over the walls of the ves-
sel and under the centrally-disposed flange on
the exterior cap and permanently closed at
5 its top, all constructed, arranged and com-
bined to operate substantially as specified.
Signed at New York, in the county of New

York and State of New York, this 3d day of
April, A. D. 1900.

ABBOT AUGUSTUS LOW.
